ATTY.

UNITED STATES PATENT OFFICE

2,362,656

CHAIN PIN INJECTOR AND EJECTOR TOOL

Harold C. Medley, Columbus, Ohio, assignor to
The Jeffrey Manufacturing Company, a corpora-
tion of Ohio

Application October 15, 1943, Serial No. 506,458

10 Claims. (Cl. 59—7)

This invention relates to a tool which is de-
signed particularly to inject or eject a pin of a
link type chain.

An object of the invention therefore is to pro-
vide an improved tool of the above-mentioned
type which can readily inject a pin into a chain.

Another object of the invention is to provide
such an improved tool for ejecting a pin from
a chain.

A further object of the invention is to provide
such a tool which can alternately inject or eject
a chain pin.

A still further object of the invention is to pro-
vide such a tool in which the pin is guided so
as to have a predetermined position with respect
to the chain link when inserted.

Other objects of the invention will appear
hereinafter, the novel features and combinations
being set forth in the appended claims.

In the accompanying drawing,

Fig. 1 is a developed view of the tool of my
invention;

Fig. 2 is a sectional elevational view of the tool
shown in operating position with respect to a
chain and showing the manner of inserting a
chain pin in place;

Fig. 3 is a partial view, similar to Fig. 2, showing
the manner of ejecting a pin;

Fig. 4 is a sectional view taken on the line
4—4 of Fig. 2, looking in the direction of the
arrows; and

Fig. 5 is a sectional view taken on the line
5—5 of Fig. 2, looking in the direction of the
arrows.

The tool of my invention is constructed partic-
ularly to inject or eject relatively large con-
necting or pivot pins which are used in fairly
heavy chains and which, at least in part, have a
tight fit with a portion of a chain link so as to
require a special tool for their injection or
ejection.

The tool includes a threaded block or head 10
which at its center threadedly receives a threaded
shaft or screw 11 provided with a tool receiving
head 12. At opposite sides the block or head 10
is provided with metal clips 13 which are at-
tached thereto by screws, and which provide
pivotal connections for a pair of spaced tension
links 14 and 15.

As illustrated in Figs. 2 and 3 of the drawing,
adjacent their bottoms the links or tension means
14, 15 carry a cross-head or base 16, the op-
posite ends of which extend into the loops of
the links 14 and 15 and rest upon the bottom por-
tions thereof and are removably and pivotally

attached thereto by spring clips 17 which are at-
tached to the base 16 by screws.

Attached to the bottom of the threaded shaft
or screw 11 is a sliding thrust block 18, the op-
posite sides of which are notched to receive the
spaced members of the links 14 and 15 which co-
operate to hold the block 18 against rotation as
the screw 11 is rotated. The connection between
the screw 11 and the block 18 is by means of a
bushed pivot pin 19 which provides for free rela-
tive rotation between the two. The lower face
of the thrust block 18 is provided with an integral
cup 20 which is adapted to receive the head 21 of
a pin 22 which is adapted to attach two links of a
chain together. The two links of the chain are
illustrated and include a pair of similar links, each
having a pair of side bars 23 which are spaced
apart at one end sufficiently to extend over the
side bars and integral knuckle 24 formed at the
other end of each link. The knuckle 24 may be
provided with a bushing 25 as illustrated in the
drawing.

In some chain constructions and in one in
which the tool of my invention may be employed,
it is necessary to have the pin 22 properly aligned
in the side bars 23 and bushing 25 because the
lower end of the pin, as illustrated in Figs. 2
and 3 of the drawing, is provided with final pin
locking grooves 26 on opposite sides thereof
which are received by a locking washer having a
keyhole opening therein which is first pressed
over the pin end and then slid longitudinally to
lock the pin with the washer, after which the
washer is welded to the adjacent side bar 23 of
the link. It is necessary to obtain this align-
ment since the pin 22 normally has a tight fit
with at least one of the side bars 23 and this
is preferably adjacent the head of the pin 22 so
that after the pin is inserted, it can not be freely
rotated.

To provide this alignment the head of the pin
22 is preferably provided with a projection 27
(see Figs. 2 and 3) which extends radially across
the head and at its opposite ends is adapted to
be received in diametrically spaced recesses 28
(see Fig. 5), formed on opposite sides of a cen-
tral recess 29 formed in the thrust block 18,
which recess 29 receives the head of the pin 19
which connects screw 11 and block 18. Thus
by inserting the pin 22 in such a position that
the projection 27 is received in the two recesses
28, the operator can be assured that the pin 22
when pressed with a tight fit between the upper
end thereof and the top side bar 23, will be in

proper position to be attached by the above-mentioned keyhole washer.

To provide for the driving insertion of the pin 22 into the overlapping side bars 23 of two adjacent links, I provide a sliding ring 30 which is attached to some element of the tool by a flexible attaching device and, as illustrated, is attached to the link 15 by a chain 31, the chain preferably being welded to said link 15 and to one side of the slide ring 30. The chain 31 also extends to the previously mentioned base or cross-head 16 and is welded to it since otherwise the base 16 might be detachable from both of the links 14 and 15 since each of the spring clips 17 provides for this detachability.

The slide ring 30 preferably has interlocking connections 32 adjacent each side which provide for and require it to be slid over the base 16 when inserted and removed, and adjacent each side of said ring 30 there is a spring clip 33 which is attached thereto by screws and which have frictional engagement with opposite curved side portions of the base 16 to hold it in proper position and to indicate to an operator when it is properly positioned to receive a pivot pin 22.

The ring 30 is provided with a central opening 34 to permit the lower end of a pin 22 to extend therethrough when the pin is being injected, as illustrated in Fig. 2 of the drawing.

The operation of the device for the injection of a pin is believed evident by reference to Fig. 2 of the drawing. The parts are assembled as there indicated, with the adjacent links of the chain between the two links 14 and 15 after the pin 22 has been dropped in place to the position indicated which can be done without any tools since the chain parts can be freely assembled to the position indicated. The pin 22 is adjusted to such a position that the projection 27 will align with and be received by the recesses 28 as the threaded shaft 11 is operated by a tool on the head 12 to move the thrust block 18 downwardly until the head 21 of the pin is received in the integral cup 20.

As the threaded shaft 11 is screwed home, the pin 22 will be forced downwardly and there will be a tight fit between the top portion thereof and the upper side bar 23. The pin 22 is, of course, free to move downwardly because of the slide ring 30 which transmits the compression force from the lower side bar 23 to the cross-head or base 16. At the upper end the compression force transmitted by the screw 11 is delivered by the thrust block 18 to the head 21 of the pin 22. The links 14 and 15 are, of course, under tension. The threaded shaft 11 is turned until the head 21 of pin 22 rests against the top side bar 23, whereupon the threaded shaft 11 is operated in a reverse direction to lift the thrust block 18 from the head 21, whereupon the tool can be readily disassembled as by detaching one of the links 14 or 15 from the base 16.

To provide for the ejection of a pin by the tool, there is another ring 35, though it is to be understood that within the scope of my invention there may be a single ring instead of the two rings 30 and 35, which may be employed alternately for injecting or ejecting a pin, depending upon whether it is positioned adjacent the upper side bar or lower side bar. Since the size of the openings in the two rings 30 and 35 is different, however, and since it is desired to provide friction guide means for the bottom ring, I preferably provide the tool with both the rings 30 and 35. The ring 35 is provided with a hole

36 which will freely pass over the head 21 of the pin 22 and it is preferably permanently attached to the block or head 10 or some other part of the tool by a flexible attaching device such as the chain 31 which is welded at one end to the ring 35 and at the other end to said head 10.

To eject the pin 22 (see Fig. 3) the ring 35 is inserted over the head 21 of said pin 22 and between the upper side bar 23 of the chain link 10 and the thrust block 18. During this operation the sliding ring 30 is removed and the bottom of the pin 22 rests in a recess 38 formed in the center of the base 16. As the screw 11 is driven home and the links 14 and 15 are placed under tension, the force of the screw 11 will be transmitted to push downwardly on the chain links, the force being transmitted from thrust block 18 through ring 35 to upper side bar 23 of a chain link. This, of course, will force the pin 22 upwardly with respect to the chain link and free the pin as soon as the tight fitting upper portion thereof is pushed out of the upper side bar 23. Thereafter the parts can be disassembled by disconnecting one of the links 14 or 15 from the base 16.

From the above description it is obvious that I have provided a very flexible tool which can be used either to inject or eject a pin of a chain and one in which the pin will be guided into proper position when it is being injected.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I wish to secure by Letters Patent of the United States is:

1. A chain tool including a head and a spaced base, spaced link tension means connecting said head and base, a shaft threaded through said head, a block attached to said shaft to provide relative rotation therewith and adapted to transmit force from said shaft to a chain pin, and ring means adapted to rest on said base and against a chain link and having an opening through which the chain pin can extend as it is forced in place by the clamping action of said threaded shaft.

2. A chain tool including a head and a spaced base, spaced tension means connecting said head and base, a shaft threaded through said head, a block having a cup for receiving a pin head and attached to said shaft and adapted to transmit force from said shaft to a chain pin, and means adapted to rest on said base and against a chain link and having an opening through which the chain pin can extend as it is forced in place by the clamping action of said threaded shaft.

3. A chain tool including a head and a spaced base, spaced link tension means connecting said head and base, a shaft threaded through said head, a block loosely connected to said shaft and adapted to transmit force from said shaft to a chain part, and ring means adapted to rest on said block and against a chain link and having an opening through which the chain pin can extend as it is forced out of place by the clamping action of said threaded shaft.

4. A chain tool including a head and a spaced base, spaced tension means connecting said head and base, a shaft threaded through said head, a block adapted to transmit force from said shaft

to a chain part, and means adapted to rest on said block and against a chain link and having an opening through which the chain pin can extend as it is forced out of place by the clamping action of said threaded shaft.

5. A chain tool including a block and a spaced cross-head, spaced tension means pivoted at opposite ends to said block and cross-head providing space for a chain to extend between them, a shaft threaded through said block, a thrust block positioned between said tension means and adapted to receive the thrust of said threaded shaft and transmit it selectively to a chain pin or a chain side bar, a ring adapted to be inserted between said thrust block and a side bar and to transmit force between them when a chain pin is being removed, and a second ring adapted to be inserted between another side bar of said pin and said crosshead when a chain pin is being inserted.

6. A chain tool including a block and a spaced cross-head, spaced tension means attached at opposite ends to said block and cross-head providing space for a chain to extend between them, a shaft threaded through said block, a thrust block positioned between said tension means and adapted to receive the thrust of said threaded shaft and transmit it selectively to a chain pin or a chain side bar, a ring adapted to be inserted between said thrust block and a side bar and to transmit force between them when a chain pin is being removed, and a second ring adapted to be inserted between another side bar of said pin and said cross-head when a chain pin is being inserted.

7. A chain tool including a head, a shaft threaded through said head, a thrust block at-

tached to said threaded shaft, tension means pivotally attached to opposite sides of said head, a base pivotally attached to one of said tension means and having means for pivotally attaching it to the other tension means, and an operating force transmitting ring attached by a flexible member to one of the aforescribed elements.

8. A chain tool including a head, a shaft threaded through said head, a thrust block attached to said threaded shaft, tension links pivotally attached to opposite sides of said head, a base pivotally attached to one of said tension links and having means for pivotally attaching it to the other tension links, and an operating force transmitting ring attached by a flexible member to one of the aforescribed elements.

9. A chain tool including a head, a shaft threaded through said head, a thrust block attached to said threaded shaft, tension means pivotally attached to opposite sides of said head, and a base pivotally attached to one of said tension means and having means for pivotally attaching it to the other tension means, said block having pin guiding means formed thereon.

25 10. A chain tool including a head, a shaft threaded through said head, a thrust block attached to said threaded shaft, tension means pivotally attached to opposite sides of said head, a base pivotally attached to one of said tension means and having means for pivotally attaching it to the other tension means, and an operating force transmitting ring attached by a flexible member to one of the aforescribed elements, said block having pin guiding means formed thereon.

HAROLD C. MEDLEY.
